UNITED STATES PATENT OFFICE.

JOSEPH E. BOHNER, OF ANSONIA, CONNECTICUT.

DESIGN FOR A FRAME FOR TABLE-TOPS.

SPECIFICATION forming part of Design No. 24,423, dated June 25, 1895.

Application filed May 11, 1895. Serial No. 549,009. Term of patent 3½ years.

To all whom it may concern:

Be it known that I, JOSEPH E. BOHNER, a citizen of the United States, residing at Ansonia, in the county of New Haven and State of Connecticut, have invented and produced a new and useful Design for Table-Top Frames and Similar Articles, of which the following is a full and complete specification, reference being had to the accompanying drawing, which illustrates the design.

The design consists of a metallic strip or frame of rectangular shape in general form, which constitutes the frame of a table top. In the drawing, one side of two corners of the frame is shown, it being understood that the other parts of the frame bear the same design. It is also to be understood that the frame usually is designed to inclose a table top of wood, onyx, marble or other material artistic to the eye.

The essential features of the design consist of the plain inner strip A, the outer strip B and the intermediate strip C, the two latter strips being separated by the nodules D. The corners are ornamented with the nodular shell-like design E E. A similar design F F is located intermediate of two corners, and between the intermediate design and the design for the corners is located the lattice shield design G G.

What is claimed as new is—

The design for the frame of table tops and similar articles, substantially as shown and described.

JOSEPH E. BOHNER.
